UNITED STATES PATENT OFFICE.

THADDEUS GRASK, OF WICHITA, KANSAS.

EXTENSIBLE MOLDING-FLASK.

1,153,063.

Specification of Letters Patent.

Patented Sept. 7, 1915.

Application filed October 12, 1912. Serial No. 725,425.

To all whom it may concern:

Be it known that I, THADDEUS GRASK, a citizen of the United States, residing at Wichita, in the county of Sedgwick and State of Kansas, have invented certain new and useful Improvements in Extensible Molding-Flasks, of which the following is a specification.

My invention relates to an improvement in extensible molding flasks such as are used in iron, steel, brass and other foundries, and the object is to provide means whereby the sides and ends are capable of being extended.

15 The invention consists of certain novel features of construction and combinations of parts which will be hereinafter more fully described and pointed out in the claims.

In the accompanying drawings,—Figure 1 is a perspective view of the assembled flask showing it in its smallest size; Fig. 2 is a perspective view with certain portions of the flask broken away showing the manner of extending the sides and ends of the flask; Fig. 3 is a detail sectional view through one of the ends; Fig. 4 is a detail sectional view through one of the sides; Fig. 5 is a detail in perspective of the inner surface of one of the sides.

20 A, A represent the side rails of the flask which are made in sections and are connected together at their inner ends by tongue and groove joints. Each side of the side rails A is preferably provided with a dovetailed groove 1, 1, in which clamping bars 2, 2 are received. Bolts 3, 3 pass through the side rails and the clamping bars for fastening them together, and nuts 4, 4 are secured upon the bolts for fastening the 25 bolts to the parts.

End rails C, C are made in sections and are connected together by tongue and groove joints at their inner ends. Angle braces 5, 5 are connected by means of bolts 6 to the end rails C and the braces are also connected to the side rails A by means of bolts 7 thereby fastening the end rails to the side rails. The end rails C are provided with longitudinal dovetailed grooves 8 in 30 which locking bars 9, 9 are received for fastening the end rails together, and bolts 10, 10 pass through the bars and end rails for fastening the bars and end rails together.

35 The inner sides of the side rails A are provided with vertical grooves 12 for the reception of the sand supporting bars 13, 13.

Rods 14 extend through the two side rails A for joining and connecting them together and preventing the side rails from spreading apart especially at the center. Connected 40 to the end rails C are the dowel pins 15 which are adapted to fit into the sockets carried by the drag (not shown). Supplemental or extension end rails 16 and side rails 17 are interposed between the end rails 45 C and the side rails A as is shown clearly in Fig. 2 when it is desired to either widen or lengthen the cope or flask frame.

The supplemental extension end rails and side rails 16 and 17 are provided with 50 tongues and grooves so that the tongue and groove joints can be carried out with these members in connection with the end and side rails, and they are provided with the longitudinal grooves for the reception of 55 the clamping bars, which clamping bars are connected to the supplemental rails by means of the bolts 10 and 3 respectively. The ends of the side clamping bars 2 and the ends of the side rails A are extended 60 for forming handles 18, 18 whereby the flask can be carried.

It will be seen from the foregoing that the side clamping bars 2 and the locking bars 9 have a sliding engagement with the 65 side and end rails so that the entire frame can be widened or lengthened, or merely widened, or instead of being made wider, it can be made longer. In this manner it is not necessary to provide a plurality of various sizes of forms as is now required in most foundries where only a small portion of the various sizes of flasks are in use at any one time and considerable space is required for storage of the unused flasks, and naturally the expense of repairs on a great 70 number of flasks is very large. In the widening of the flask it is necessary to provide larger bars 13.

75 It is evident that slight changes might be made in the form and arrangement of the several parts described without departing from the spirit and scope of my invention, and hence I do not wish to be limited to the exact construction herein set forth.

Having thus described my invention, what I claim as new and desire to secure by Letters Patent is—

80 1. In a molding flask, the combination with sectional side rails provided with longitudinal grooves in the side walls thereof, of end rails connected to the side rails and

clamping bars slidably mounted in the grooves of the side rails for fastening the sections of each of the side rails together.

2. In a molding flask, the combination with sectional side and end rails provided with longitudinal grooves in the sides thereof, of clamping bars slidably mounted in the grooves of the side and end rails for connecting the sections of each of the side and end rails together.

3. In a molding flask, the combination with extensible sectional side and end rails provided with longitudinal grooves in the sides thereof, of clamping bars slidably mounted in the grooves of the side and end rails for connecting the sections of each of the side and end rails together.

4. In a molding flask, the combination with extensible side rails having longitudinal grooves in the sides thereof, end rails connected to the side rails, clamping bars seated in the longitudinal grooves of the side rails for fastening the sections of the side rails together, and said side rails provided with vertical grooves for the reception of the ends of the sand supporting bars.

5. In a molding flask, the combination with extensible sectional side and end rails, said side and end rails connected together and provided with longitudinal grooves, of clamping bars received in the longitudinal grooves for fastening the sections of the side and end rails together, and means for locking the clamping bars to the side rails for holding the various sections of the side and end rails together.

6. In a molding flask, the combination with extensible side rails, having longitudinal grooves in the sides thereof, clamping bars slidably mounted in the longitudinal grooves of the side rails for fastening the sections of the side rails together, said side rails provided with vertical grooves on one

side above and below the longitudinal grooves, and sand-supporting bars located between the side rails and the ends of the bars received in the vertical grooves of the side rails.

7. In a molding-flask, the combination with sectional side and end rails having grooves on their opposite faces, of clamping-bars slidably fitted in said grooves, and bolts passing through said side and end rails and clamping-bars.

8. In a molding-flask, the combination with sectional side and end rails having dove-tailed grooves on their opposite faces, of clamping-bars slidably fitted in said grooves, and bolts passing through said side and end rails and clamping-bars.

9. In a molding-flask, the combination with sectional side and end rails and sand-supporting bars, the side and end rails having longitudinal grooves in their opposite faces, of clamping-bars fitted in said grooves, the inner clamping-bars of the sides locking the supporting bars against removal.

10. In a molding-flask, the combination with sectional side and end rails, the adjacent ends of the sections of which have a tongue and groove joint and the sides of which have longitudinal grooves, of supplemental or extension end and side rails correspondingly constructed with a tongue at one end and a groove at the other, and side grooves, clamping-bars constructed and adapted to fit said side grooves, and means for fastening the said parts together.

In testimony whereof I affix my signature, 80 in the presence of two witnesses.

THADDEUS GRASK.
